UNITED STATES PATENT OFFICE

2,583,490

BOX DUMPING MACHINE

Don S. Orlando, near Cupertino, Calif.

Application May 19, 1947, Serial No. 748,996

7 Claims. (Cl. 214—1.1)

1

This invention concerns a box dumping-machine of the general type disclosed in the patents to Thompson et al., No. 1,926,318, of September 12, 1933, and to Northrup, No. 766,515, of August 2, 1904. The present application is in part a continuation of my copending application Serial No. 583,775, filed March 20, 1945, entitled Box Dumping Machine, now Patent No. 2,424,252, issued July 22, 1947.

In such box dumping machines, as ordinarily used, a stack of field boxes, four or five high and each loosely filled with fruit, is delivered to elevator means, whereby as the stack is gradually lifted, and each topmost box arrives at a pickup station, box-gripping means, properly synchronized with the elevator or conveyor, engage and lift and thereby separate this topmost box from any boxes in the stack which remain beneath it, or from the elevator platform. Each such box is conveyed by the box-gripping means, or by subsequent means, through a box-dumping station where the box is tilted over or inverted, and finally to a releasing station where the empty box is released for transportation back to a collecting point for reuse. The fruit, as it is dumped, is conveyed away for subsequent operations upon it, collectively or singly.

Proper synchronization between the slow upward movement of the stack elevator and the more rapid movement of the individual box-gripping members through and past the pickup station is essential in such box-dumping mechanism, and adjustability or flexibility in such synchronization is also desirable for proper exactitude. The elevator becomes a problem as soon as the last box is lifted from it, for if it continues upwardly with its normal endless chain support, it may interfere with the box-gripping and fruit-receiving means; if it is disconnected from the chain for reverse movement downwardly to the stack-receiving level, synchronization between the stack elevator and the box-gripping members is interrupted, and must be automatically restored, with a minimum of lost time. In the gripping of the individual boxes provision must be made for securing a firm grip on each box across a sufficiently broad base, or along a sufficiently extended line, that the box is held firmly and immovably with respect to the box-gripping members, yet without any possibility of engaging or interfering with the fruit within the box, either while the box is being lifted or while the fruit is being dumped from the box.

The present invention is directed to the solution of the problems indicated. Somewhat more

2

specifically, it is one object of the present invention to provide box-gripping members which alone, or in conjunction with other members, will serve to steady the box merely by engagement with its opposite faces or ends, and which additionally is locally self-conforming to boxes slightly differently positioned or of slightly different size.

It is also an object of this invention to provide a stack elevator which is elevated by a continuously advancing conveyor mechanism in the nature of an endless chain, which latter is properly synchronized at all times with the continuously moving box-gripping means, yet to permit disconnection of the elevator platform from the conveyor mechanism, and its reconnection therewith, in such manner that the stack-elevating platform itself merely rises and falls between a lower stack-receiving level and an upper level in the vicinity of the box-gripping station, and can only be reconnected to the endless chain in proper synchronization with the latter and, therefore, with the box-gripping mechanism. It is also an object, in connection with such mechanism so arranged, to provide for automatically releasing the elevator from its conveyor mechanism when the last box has been lifted from it, to permit the elevator's prompt downward return to the stack-receiving level; also, it is an object to effect resynchronization thereof automatically, but as a result of conscious action by an attendant, whereby such time as is necessary for properly positioning a new stack of boxes to be raised, or to accommodate breaks in the smooth flow of stacks to the machine, can be provided.

It is also an object of this invention to provide simple mechanism for accomplishing and controlling the box-gripping and releasing movements of the box-gripping members at the appropriate stations, and in this connection it is a further object to provide means whereby some adjustment may be accomplished of the point where the box-gripping members take hold of the box, thus effecting closer synchronization between the stack-elevating means and the individual box-gripping means.

It is also an object to provide a further simplified form, as a modification of the preferred form, wherein the mechanism for gripping and releasing the boxes is reduced to the minimum of simplicity.

With these objects and others in mind, as will appear as the specification progresses, my invention comprises the novel box-dumping mechanism as a whole, the novel parts thereof, and the

novel combination and relative arrangement of these parts, all as shown in the accompanying drawings, as will be described in this specification, and as will be more particularly pointed out by the claims at the end hereof.

In the accompanying drawings the invention is shown in somewhat diagrammatic fashion, embodied in a preferred form and also in a somewhat modified form.

Figure 1 is in general a side elevation of the box-dumping machine, and Figure 2 is a plan view of the same, somewhat enlarged.

Figure 3 is a sectional view taken on a vertical plane through the stack-elevating platform and its associated parts.

Figure 4 is an isometric view of the complete set of box-gripping members and auxiliary members for engagement with one end of a box, and Figure 5 is in general a part-elevational view and part-sectional view through the same.

Figure 6 is a plan view somewhat similar to Figure 2 of a modified form of the box-gripping members, and Figure 7 is a detail sectional view through the same taken substantially at the line 1—1 of Figure 6.

Omitting consideration of the stack elevator until later, it may be assumed that the individual boxes B are presented at proper intervals to a pickup station P, there to be engaged by box-gripping or -engaging members so that each such box is held immovable with respect to such members, and by them is lifted from the pickup point P, is carried through and tilted over or partially inverted by the time it reaches a dumping station D, and then is carried on to a station R which is substantially diametrically opposite the pickup station P, at which station R the box is released, to be borne off by suitable means, while the box-gripping members which held it continue on in a closed path, so that eventually they arrive again at the pickup station P in time to pick up another box, if one be waiting there. Preferably there are several sets of box-gripping members, angularly spaced one behind another, so that it is not necessary to wait for one individual set of box-gripping members to return to the pickup station P before a second box is picked up, but rather, in the arrangement shown there are four sets of box-gripping members, movable in a circular path, so that each one picks up every fourth box, assuming always that there is a box waiting at the pickup station P.

A rotative shaft 1 driven from the motor M, by means such as the drive chain 49, carries two axially spaced sets of radial arms 10 which constitute supports for the box-gripping members. Each arm at a given end of the shaft is complemented by an opposite arm at the other end of the shaft.

The box-gripping members, as shown, are of two kinds. Either kind may be used alone, or if used conjointly, each will supplement the other. For convenience the members 2 may be termed the primary box-gripping members and the members 3 may be termed the auxiliary box-gripping members. The members 2 are similar to those disclosed in my copending application referred to above, and grip adjacent opposite corners of the box so that, there being four of them, the four corners of the box are gripped simultaneously. It was found, however, that these alone would not always grip and hold a filled box sufficiently securely, particularly if the box happened to be slightly displaced as it arrived at the pickup station, or if it happens to vary slightly from the

normal size. The box-gripping members 3 were devised, therefore, as auxiliary box-gripping members to steady the box while gripped by the members 2, but subsequently it was found that

5 the box-gripping members 3, by themselves, might serve adequately in the absence of the members 2. The members 3 are in the nature of bars which extend across the face outward of the box, or the end, as illustrated, and engage the box 10 along a line sufficiently extended in length to steady the box. The two members 3 press directly toward one another to squeeze the box between them.

Upon a furcated extension 11 of each radiating 15 arm 10 a lever 20 is pivotally supported at 21 between its ends, and supports the radially outermost of the gripping members 2. A similar lever 22 pivoted at 23 is formed with gear segments meshing with complementary gear segments, as 20 indicated at 24 in Figure 4, whereby to reverse the direction of swing of the lever 25 which carries the radially innermost of a pair of gripping members 2. The levers 20 and 22 are connected by the link 26, and this system of levers is 25 rocked, to cause the paired members 2 to approach one another or to recede from one another, by means such as the rod 40 and link 41, the latter connected at 42 to the lever 22.

Each bar 3 is carried upon two or more parallel 30 links 39 from the extension 11, and is moved inwardly toward the opposite bar or outwardly away from the same by means of an actuating lever 31 pivoted at 32 upon the extension 11, and connected by a link 33 to the pivot 42 where the link 41 and rod 40 connect to the lever 22. The parts are so organized and arranged that whenever the pair of members 2 are swung towards one another to grip a box, the bars 3 are swung inwardly also to grip the box, and vice versa.

40 Preferably, each of the members 2 and 3 is mounted, with respect to its immediate support, for limited yielding, as, for example, by the springs 27 and 37. Stop means 28 and 38 limit the movement of these members under the influence of their springs. In addition, it is preferred that the box-engaging faces of each be of relatively soft rubber, not only for gripping, but for conformance locally to variations in position or size and shape of the box.

50 Since the arms 10 and their extensions 11, with the thus-supported box-gripping members 2 and 3 and their actuating mechanisms, rotate about the axis of the shaft 1, it is convenient to time and control their movement by a fixed cam 4 of suitable shape. Such a cam would have an abrupt rise, as indicated at 43 in Figure 1, to effect movement of the box-gripping members into engagement with the box at the pickup station P, and would have a similar and almost as abrupt drop at 44 to effect release of the boxes at the releasing station R. Intermediate these drops it may be substantially of circular conformation. Motion is communicated to the rod 40 preferably through a bell crank lever 45 pivoted on the arm 10 at 46 and having one end connected through a link 47 with the rod 40 and carrying at its other end a cam follower roller 48. A spring 29 urges the rod 40 inwardly.

55 Since it may be desirable to effect some slight angular adjustment of the position of the cam surfaces 44 and 46, in order that the box-gripping members may engage the more slowly moving box precisely at the proper instant at the pickup station P, the cam, while fixed in the ordinary sense during operation, is nevertheless slightly

adjustable with respect to the frame brackets 90 by means such as the arcuate slots and clamping bolts at 49.

Dumping of the fruit commences when the box has been sufficiently elevated somewhat above the pickup point P and has been tilted sufficiently by its advance through a given angular amount toward the dumping station D. Means must be provided beneath the dumping point to receive the fruit and to start it on its way. To that end I provide a belt or moving apron 5 disposed intermediate the arms 10 and passing about rollers 50, 51, and 52, and about the shaft 1, which drives it. This mechanism may be supported in part from brackets 56 which are part of an inclined chute 54 down which the fruit slides, to be received upon an off-bearing conveyor belt 55.

The boxes, upon arriving at the releasing point R, being released by the cam follower roller 48 passing down the incline 44, are deposited upon an off-bearing belt or similar conveyor C, by which they can be conveyed to a distant point for collection and reuse.

The boxes, in stacks of four or five, are brought in on hand trucks or the like, and are deposited on the level S adjacent the platform 6. This platform is supported upon brackets 60, supported and guided by rollers 61 running in an upright channel guide 62. Adjacent the guide 62 is a second guide 63, wherein runs the upwardly trending run of an endless conveyor chain 64 or the like, which is driven continuously and at a steady rate from the motor M by suitable drive means, such as the chain 65. The chain 64, then, is synchronized with the drive of the arms 10, and runs continuously, as the arms rotate continuously.

The platform, however, is only intermittently connected to the chain 64 for elevation by the latter. When connected, care must be taken to insure synchronization between the time of arrival of the topmost box of a stack on the platform at the pickup station P, and the arrival at that station of a set of box-gripping members. The box-gripping members move appreciably more rapidly than the boxes are elevated by the platform, and proper synchronization at this point is essential.

To these ends a releasable interengagement is provided between the platform and the conveyor at definite intervals along the length of the conveyor. Thus at suitable intervals the conveyor has register means in the form, for instance, of a laterally projecting pin 66, wherewith may be engaged a bolt 7 carried by and slidably laterally with respect to the platform 6, provided the bolt is projected into the path of the register means 66.

The bolt 7 is biased by means such as the spring 70, for retraction out of the path of the register pin 66, but the bolt 7 may be projected into the path of the register means by depression of a pedal 71, or by any equivalent means. It is held in such projected position by a dog 72, engageable within a notch 73 in the bolt, and this dog, pivoted upon the platform, has an end 74 which projects into the path of a fixed trip 75, located adjacent the upper end of the travel of the platform, that is to say, in the vicinity of the pickup station P. Following movement by the pedal of the bolt 7 into pin-engaging position, a spring 76 withdraws the pedal 71 from its position behind the bolt 7 when the pedal is released, and the bolt has been engaged by the dog 72

to latch it in its projected or pin-engaging position.

A stack of boxes B is moved over the platform 6 in the lowered position of the latter, which is slightly below the stack-receiving level S. The operator steps on the pedal 71 and then releases it, and now the bolt 7 has been projected, and lies in the path of the next arriving register means 66. The position of the latter is in rigid synchronism with the rotation of the arms 10. As the register means 66 arrives beneath the bolt 7, it engages the bolt, and thereby lifts the platform and the stack of boxes upon the platform. The stack of boxes is elevated, and as the topmost box in turn arrives at the pickup station P, it is gripped and lifted by the box-gripping members 2 and 3, and is gradually inverted as it passes through the dumping station D, and when it finally reaches the releasing station R it is released, and is carried off by the conveyor C. The fruit, in the meantime, has tumbled upon the apron 5 and down the chute 54, to be carried off by the off-bearing conveyor 55. When the last or lowermost box of a stack has been lifted at the pickup station P, the trip end 74 of the dog 72 is immediately engaged with the fixed trip 75, releasing the dog from its engagement with the bolt 7, permitting the bolt to withdraw from supporting engagement above the register pin 66, and immediately the empty platform drops. Its downward movement may be slowed by damping or counterweighting means, or its arrival at the bottom may be cushioned by suitable cushioning means, none of which has been shown, since any convenient means to these ends may be employed, and such means are known. The platform is then ready to receive a following stack, and again starts upwardly.

It will probably happen that one or more arms 10 will pass the pickup station P while the platform is dropping, while a new stack is being placed thereon, and while the platform is rising to bring the topmost box to the pickup station. This is not harmful, for equivalent delays would arise in other stages of the operation, and it is in fact desirable to permit intervals between the dumping of a stack of boxes and the dumping of the next stack, in order to permit following operations to be performed with sufficient care.

In Figures 6 and 7 a simplified form of the box-gripping members and their actuating means is shown. The elevator, the fruit-receiving apron, and like accessories have been omitted for clearer showing. In these views only the box-gripping members 3' are employed, and these are pivotally mounted at 34, between their ends, upon the radial arms 12', which correspond generally to the arms 10, but which in this instance are pivoted upon a transverse axis 13, which intersects the axis of the shaft 1, so that the arms 12' may rock to a limited extent each about its transverse axis 13. Each box-gripping member 3' is supported yieldably from its supporting arm 12' by the springs 35.

Tilting of the arms 12' about their transverse axes 13 is accomplished by means of the cam follower rollers 14, which engage the crowned cam 4', which, like the cam 4, is fixed. The arrangement is such that as the arms 12' are tilted to cause approach of the box-gripping members 3' at the pickup station P, they are separated at the opposite ends of the arms 12', to release the box at the releasing station R. Between these stations the box-gripping members are maintained in firm engagement with the opposite

ends of a box, and thus transport the box through the dumping station D. The rubber face of each, and the conformance by means of the springs 35, permit the box-gripping members 3' to accommodate themselves to boxes slightly differently positioned, or slightly varying in size and shape from the normal, and yet to grip each box securely.

I claim as my invention:

1. Box-dumping mechanism comprising two axially spaced supports rotative conjointly, a box-gripping element carried by each support, outwardly of its rotative axis, facing and coacting with the like element on the axially-spaced support and mounted for movement towards and from the same, and formed for engagement with a box along a line across the end wall of such a box while it is disposed alongside the rotative axis, further box-gripping elements carried by each support, in position to engage the opposite side walls of such a box so disposed, adjacent the box's corners, means to present individual boxes at a pickup station, in position to be so engaged, means to rotate the supports to present the several coacting box-gripping elements at the pickup station as such a box arrives there, and means controlling the several coacting box-gripping elements so to engage such box at the pickup station substantially simultaneously, to retain it relatively immovable, though rotative bodily with the supports, as it is carried and tilted through a dumping station, and to release the box at a releasing station beyond the dumping station.

2. Box-dumping mechanism as in claim 1, the control means being formed as a cam nonrotatively fixed, and means to adjust the cam angularly about the axis of rotation, to vary the point of engagement of the box-gripping means with the box.

3. Box-dumping mechanism defined in claim 1, wherein the control means includes separate mounting means for each of the first-mentioned gripping elements, operable to move such gripping means toward and from its support, out of and into engagement with the adjacent end face of a box, and yieldable resilient means interconnecting each such first-mentioned gripping elements and its mounting means to enable relative movement of said mounting means toward the end face of a box after gripping engagement of such end face by said gripping elements.

4. Box-dumping mechanism defined in claim 1, wherein the control means controlling a pair of the further gripping elements and the associated first-mentioned gripping elements includes a cam, a cam follower engaging such cam and mounted on the support for all such gripping elements for rotation conjointly therewith, separate means operatively interconnecting said cam follower with such pair of further gripping elements and with such first-mentioned gripping elements for conjoint operation of all thereof by relative rotative movement of said cam follower over said cam, and yieldable resilient means included in each of said separate connecting means for yielding of either of such connecting means should either the first-mentioned gripping ele-

ments or the pair of further gripping elements connected thereto, as the case may be, come into gripping engagement with the box before the other may do so, thereby to insure gripping of such box by all of said elements uniformly irrespective of minor variations in position and size of individual boxes.

5. Box dumping mechanism comprising two axially spaced supports rotative conjointly, a box-gripping bar carried by each support outwardly of its rotative axis, for shifting each towards and from the bar on the opposite support, said bars when farthest separated being spaced sufficiently to receive a box between them, and when closest together grippingly engaging the opposite axially spaced faces of such box, means restraining rotation of each bar on its support about any axis parallel to the support's axis of rotation, auxiliary gripping means carried by the respective supports, complemental to each pair of box-gripping bars, in position to engage with the box adjacent its corners, cam means operatively connected to said bars and to the corresponding auxiliary gripping means for conjoint movement to engage them with and disengage them from each individual box substantially simultaneously, by rotation of said supports, and means to rotate said supports, with said bars, said auxiliary gripping means, and the thus-engaged box, said cam means being arranged to effect gripping engagement of a box as the bars are rising through a pickup station, to retain such engagement as the box tilts through a dumping station, and to release the box at a release station, beyond such dumping station.

6. Box-dumping mechanism as defined in claim 5, including bar-mounting means to support each bar from its support, said bar-mounting means being individually and locally resiliently yieldable, in a direction generally parallel to the axis of rotation, to accommodate boxes which are initially misplaced somewhat at the pickup station, or which depart somewhat from standard length.

7. Box-dumping mechanism as defined in claim 6, including resiliently yieldable box-engaging elements carried by each auxiliary gripping means, and movable with the same to engage the side walls of each box adjacent the latter's corners, said box-engaging elements by their resilient yielding accommodating boxes which are initially misplaced somewhat at the pickup station, or which depart somewhat from standard width.
